The ornamental design for the communication headset, as shown and described.

DESCRIPTION

FIG. 1 is a front perspective view of a communication headset showing my new design;

FIG. 2 is a front elevation view in an alternate position thereof;

FIG. 3 is a left side elevation view of FIG. 1 thereof; FIG. 4 is a left side elevation view of FIG. 2 thereof; FIG. 5 is a right side elevation view of FIG. 1 thereof; and, FIG. 6 is a top plan view of FIG. 1 thereof.

A communication headset having ear cups having mirror image ear cup cushions, a head band connecting the ear cups and capable of articulating about the connections to the ear cups, and a boom microphone. The housings of the ear cups are not mirror images. The ear cups support, variously, forward pointing microphone openings, a boom microphone, pushbuttons, switches, and slots. The characteristic features of the design resides in the articulable headband and in the pattern of external switches, pushbuttons, microphones, and slots on the ear cup housings.

The broken lines depict environment that forms no part of the claimed design.
